LORENZO H. GILSON, OF BROCKTON, MASSACHUSETTS, ASSIGNOR TO PERLEY E. BARBOUR, OF QUINCY, MASSACHUSETTS, DOING BUSINESS AS BARBOUR WELTING COMPANY, OF BROCKTON, MASSACHUSETTS

WELT SHOE AND WELTING THEREFOR

Application filed June 16, 1928. Serial No. 285,805.

This invention relates to the manufacture of welt shoes and to welting therefor specially prepared for sewing a buried or hidden out-seam.

5 Heretofore, in order to bury the outseam in the welt, manufacturers have employed the well known "fudge stitch" which requires closing the two lips of the slit over the sewed seam. Of late years ornamental welting has 10 gained great popularity. Ornamentation of 15 welting takes various forms in some of which cuttings are made in the exposed surface providing two planes which may be stained in differing colors. An example of one such surface cutting is disclosed in the Lyon United States Patent No. 1,054,225, granted February 25, 1913, for welting for sewed boots and shoes. Those skilled in the art will recognize that if welting, cross cut as 20 illustrated in said Patent No. 1,054,225, is fudge stitched the lips of the slit cannot be laid back evenly, as can be done on plane surfaced welting, resulting in a rough seam line showing on the surface that mars the 25 finish and is not acceptable.

A special object of the present invention is to provide for a buried stitch in ornamental welts, such as the cross cut type referred to, that will not affect the ornamentation. 30 Accordingly the invention resides in cutting a lip from the exposed face of the welt, that may be turned or lifted to permit the outseam to be sewed in the flesh beneath it and then laid back over the sewed seam. For perfection in shoemaking the channel, which produces the lip, is cut from the inner margin of the welt outward. This preserves the material advantage of an integral outer edge on the welting. In its broader aspects the invention comprises welting fitted in the novel manner hereinafter described for sewing buried outseams and in the shoe having such a sewed outseam.

The invention will best be understood by 45 reference to the accompanying drawing showing the best form of the invention at present known, in which all the figures are shown in perspective and

Figure 1 illustrates a portion of a strip of 50 Goodyear welting of usual dimensions and

fitted in the usual manner with a groove and a bevel;

Fig. 2 illustrates the additional fitting provided by this invention, namely, a lip on the exposed or grain surface;

Fig. 3 illustrates the grain surface lip lifted to expose the underlying flesh;

Fig. 4 illustrates a portion of a welt shoe just after the outsole stitcher has sewed the 60 outseam; and

Fig. 5 illustrates a portion of another welt shoe showing a welt, ornamented by staining and cross cutting, sewed to the outsole in the manner taught by this invention.

In the embodiment of the invention illustrated in the drawing a strip of Goodyear welting 10, having a stitch-receiving groove 11 and a grain bevel 12, is channeled on its exposed or grain surface. The channel 14 (Fig. 2) is cut from the inner margin of the 70 welt outward and produces a lip 16 that may be lifted, as shown by Fig. 3, to expose the flesh 17 beneath it for stitching, cementing or any other required operation.

The welt of this invention is inseamed preferably with the channel 14 closed, as illustrated in Fig. 2, and the outsole stitcher is provided with a suitable tool for lifting or turning the lip 16, substantially as illustrated by Fig. 4, operating in advance of the stitch-forming mechanism. Preferably after the outseam 18 has secured the outsole 20 to the welt 10, the flesh 17 or both the flesh and under side of the lip are cemented and the lip is laid back in the channel as illustrated by 85 Fig. 5. The lip 16 may be lifted from its channel 14 and the channel cemented prior to the outseam sewing operation. In this event the outsole stitcher might be provided with a tool for laying the lip on the cemented 90 channel immediately after the outseam is sewed.

The generally used shoemaking processes up to the securement of the outsole, need not be altered in handling this new welting. As 95 already stated the grain-side-channeled welting passes through the welt guide of the welt sewing machine like unchanneled Goodyear welting and is secured by an inseam 22 to the upper materials 23 and insole 24. In 100

Fig. 5 there is shown a welt 25 ornamented by cross cutting and illustrating graphically how the ornamental surface is preserved from distortion by burying the outseam beneath the lip lying in the grain side channel.

5 It will be observed that by the use of a grain side channel that is cut from the inner margin outward, the outer edge of the welt is not cut into and presents an unbroken surface for finishing just the same as when the outseam is surface stitched or fudge stitched, and in addition the exposed face of the welt is left whole and unmarred by cutting because the longitudinal cut, to produce the 10 channel, is so far inward that it is hidden by the upper.

15 The nature and scope of the invention having been indicated, and its preferred embodiment having been specifically described, what is claimed as new, is:—

20 1. A welt shoe having a welt inseamed to the upper materials and insole, and an outsole outseamed to the welt by a stitch buried beneath a lip cut in the grain side of the welt from the inner margin outward to preserve 25 an integral outer edge on the welt.

25 2. Shoe welting having a grain side lip extending longitudinally thereof, the outer edge of said lip being integral with the 30 central stock of the welt body and its inner edge being free throughout the length of the welting.

35 3. Shoe welting having its grain side partially severed longitudinally to produce a lip, the free edge of said lip being within the inner edge of the welt body and the attached edge of said lip being adjacent the outer edge of the welt body but leaving a substantial integral outer margin.

40 In testimony whereof I affix my signature.
LORENZO H. GILSON.
